UNITED STATES PATENT OFFICE

133,117

DESIGN FOR A SUPPORT FOR TELEPHONE BASE AND HAND SET

Roderick R. Mathieson, Grosse Pointe Park, Mich.

Application October 27, 1941, Serial No. 103,912

Term of patent 14 years

To all whom it may concern:

Be it known that I, Roderick R. Mathieson, a citizen of the United States and a resident of Grosse Pointe Park, in the county of Wayne and State of Michigan, whose post office address is 870 Trombley Road, Grosse Pointe Park, Michigan, pray that Letters Patent may be granted me for the term of three and one-half years for the new, original, and ornamental Design for a Support for Telephone Base and Hand set, of which the following is a specification, reference being had to the accompanying drawings, forming a part thereof.

Fig. 1 is a front perspective view of a support for telephone base and hand set showing my new design.

Fig. 2 is a rear perspective view thereof.

I claim:

The ornamental design for a support for telephone base and hand set, substantially as shown.

RODERICK R. MATHIESON.
